United States Patent Office.

WILLIAM BAXTER, OF NEWARK, NEW JERSEY, ASSIGNOR TO HIMSELF AND WILLIAM D. RUSSELL, ASSIGNS TO BAXTER WRENCH COMPANY.

Letters Patent No. 86,802, dated February 9, 1869.

IMPROVEMENT IN HANDLES FOR TAPS, AUGERS, DRILLS, &c.

The Schedule referred to in these Letters Patent and making part of the same.

To whom it may concern:

Be it known that I, WILLIAM BAXTER, of Newark, in the county of Essex, and State of New Jersey, have invented certain new and useful Improvements in Handles or Wrenches for Taps, Reamers, Drills, Augers, and other tools; and I hereby declare the following to be a full, clear, and exact description of the same, reference being had to the accompanying drawings, in which—

Figure 1 is a perspective view of a tool-handle or wrench, made in accordance with my invention, and

Figure 2 is a longitudinal central section of the same.

In ordinary tap-wrenches or handles, designed to be applied to tools of various sizes, the series of holes intended to fit the different tools, extends along the wrench or handle in the direction of its length, and, consequently, all but one of the holes are removed from the centre of the handle, which is not only productive of inconvenience, but often is the cause of damaging or breaking of the tap or other tool with which the handle is used.

The primary object of my invention is to obviate this difficulty; to which end,

It consists of a wrench or handle, provided at its centre with a metal ball or boss, in which is formed a series of holes, of different sizes, to fit correspondingly-sized tools, each hole being central to the length of the handle.

A further object I have in view, is to construct the handle or wrench in such manner that, without increasing the weight, it may be made of a size sufficiently large to be easily grasped and held with the hand without discomfort; that, when made of malleable iron, it may be more thoroughly annealed; and that it may have greater strength with less material than has heretofore been practicable.

These important advantages I attain by making the wrench hollow or tubular, the shape of the core corresponding very nearly to the exterior form of the handle, excepting at the centre, where the boss is located, this part being left thicker, so as to give strength where it is most required.

In the drawings, the handle A is provided with the central boss B, the two being cast in one piece.

In the boss are formed the different-sized holes, a, for the purposes hereinbefore indicated, arranged as seen in the drawing, so that each hole is located midway between the two ends of the wrench.

The holes may, of course, vary in number and shape, according to the size of the boss, and size and shape of the different tools to which it is to be applied; and, with respect to the boss itself, it is manifest that it may be ball-shaped, as shown in the drawing, or of any other form adapted to the purpose.

By this arrangement, all the holes are equidistant from the end of the handle, and thus all unequal strain or bearing upon the tool is avoided, and the handle itself is made stronger and more convenient for use.

The tubular structure of the wrench or handle is shown clearly in fig. 2, and I greatly prefer to thus construct it. The weight of the tool is much lessened thereby, it can be made of a comfortable size for the hand, and the metal, if malleable, can be annealed more quickly, inexpensively, and thoroughly, than if it were solid, as is well known to those acquainted with this branch of the industrial arts.

The metal thickens toward the central boss B, which is nearly solid, greater strength being required at this point than at points further removed from the centre.

It will be, of course, understood that the wrench may be cast or formed in any other suitable manner, and that it may either be cast hollow, or the coring-out may be effected after casting.

Having described my invention, and the manner in which the same is or may be carried into effect,

What I claim, and desire to secure by Letters Patent, is—

The herein-described handle or wrench for taps and other tools, the same, whether tubular or not, being provided with a central boss, in which two or more holes or sockets are formed, substantially as and for the purposes shown and set forth.

In testimony whereof, I have signed my name to this specification, before two subscribing witnesses.

WILLIAM BAXTER.
